UNITED STATES PATENT OFFICE.

JESSIE B. WILLIAMS, OF GRANITEVILLE, SOUTH CAROLINA.

BEARING.

Application filed October 27, 1921. Serial No. 510,685.

To all whom it may concern:

- Be it known that JESSIE B. WILLIAMS, a citizen of the United States, residing at Graniteville, in the county of Aiken and State of South Carolina, has invented certain new and useful Improvements in Bearings, of which the following is a specification, reference being had therein to the accompanying drawing.
- 10 My invention relates to new and useful improvements in bearings and more particularly to a bearing adapted for use in connection with the whip roll stand or whip roll bearing of looms.
- 15 The principal object of the invention is the provision of a bearing, of the character described, which may be used in connection with the whip roll stands of whip roll bearings now commonly in use, my improved 20 form of bearing being adapted for easy placement or renewal.

Another object of the invention resides in the provision of a bearing constructed of wood or other similar fiber which may be 25 saturated with oil, or other lubricant, said saturation doing away with further lubricating of the parts and preventing stains upon the cloth or yarn carried by the loom.

With the above and other objects in view, 30 which will appear as the description proceeds, my invention consists in the novel details of construction, and arrangement of parts, described in the following specification and illustrated in the accompanying 35 drawings, and while I have illustrated and described the preferred embodiments of the invention it will be understood that such changes may be made as will fall within the scope of the appended claims.

40 In the drawings:—

Fig. 1 is a side elevation of a whip roll stand or bearing showing my improved form of bearing block applied thereto.

Fig. 2 is a side elevation of my improved 45 form of bearing block.

Fig. 3 is a top plan of the block shown in Fig. 2.

Fig. 4 is a side elevation showing a slightly 50 modified form of whip roll bearing and bearing block used in connection therewith.

Fig. 5 is a side elevation of the block shown in Fig. 4, and

Fig. 6 is a top plan of the block shown in Fig. 5.

55 In carrying out my invention 1 indicates a whip roll stand or bearing, of usual con-

struction, having an elongated opening 2 adjacent the lower end for adjusting purposes. At the upper end the stand is provided with the recesses 3 which in the ordinary form of stand form the bearings for the rolls. My invention consists in providing a removable bearing block 4 adapted for use in connection with the stand or bearing 1 said block being preferably of hickory although it might be of maple or other similar fiber. The block has on the lower edge a plurality of tongues or projections 5 adapted to be received in the recesses 3. A recess 6 is formed in the upper edge of the block, intermediate the ends thereof, and forms a bearing for the rolls. As shown in Figs. 1 and 2 of the drawings this recess 6 is preferably slightly off center so that the position of the roll, with respect to the loom, 70 may be adjusted as desired. The block is provided at each end with an overlying tongue or projection 7 which extends over the ends of the stand or bearing 1. The block 4 is preferably of the same width as the stand or bearing 1, as shown more particularly in Fig. 3 of the drawings, and will be saturated with oil or similar lubricant.

In Figs. 4, 5 and 6 of the drawings I have 85 illustrated a slightly modified form of bracket or bearing and bearing block to be used in connection therewith. In this form of the invention the bracket or bearing is indicated at 8, being similar to constructions now commonly in use upon looms, and this bracket is provided adjacent one end with an opening 9 to receive a shaft or other suitable support. Adjacent the opposite end the bracket has the recesses 10 formed in its upper face, 90 said recesses ordinarily forming bearings for the rolls of looms. My improved form of bearing block, used in connection with this form of bracket, is shown at 11 and is provided on the lower edge with the longitudinally 95 spaced tongues or projections 12 adapted for insertion in the recesses 10. A recess 13 is formed in the upper edge of the block and forms a bearing for the rolls. The block 11 is also provided on the forward 100 end with an overlying projection 14 extending over the forward end of the bracket, and the rear end is provided with the projection 15, extending for some little distance over the upper face of the bracket. The 110 block 11 will preferably be of the same width or thickness as the bracket and will

be saturated with oil or other suitable lubricant.

From the above detail description it will be seen that I have provided a bearing block 5 adapted for use in connection with the whip roll stand or bearings now commonly in use, the said bearing block being constructed of wood or similar fiber saturated with oil or other lubricant. The bearing block may be 10 readily placed in position and is held there-in without the use of screws or similar fastening devices, the projections on the bearing block being of such a size and shape as to snugly fit the bearing recesses now com- 15 monly provided in whip roll stands or bearings used in connection with looms. After the bearing blocks have been installed it is not necessary to again lubricate them, this means a saving of oil, and prevents oil stains 20 in the cloth or in the yarn. As shown and described in the block described in Figs. 1, 2 and 3 the bearing recess 6 is slightly off center. I have this recess off center so that when the stand is bolted to the loom the 25 whip roll shaft will be parallel over the frame of the loom in order to make the let off arm perpendicular so that it will cause the loom to let off correctly. As previously stated while the bearing block is preferably made 30 of hickory it might, if desired, be made of maple or other suitable fiber.

Having fully described my invention what

I claim as new and desire to secure by Letters Patent is:

1. The combination with a whip roll stand 35 or bearing, having longitudinally spaced recesses on its upper face, of a removable bearing block, said removable bearing block having a recess in its upper face and longitudinally spaced projections on the lower 40 edge adapted for reception in the recesses.

2. The combination with a whip roll stand 45 or bearing having longitudinally spaced recesses in its upper face, of a removable bearing block, said removable bearing block having a recess in its upper face, longitudinally spaced projections on its lower edge adapted for insertion in the recesses of the stand or bearing, and end projections adapted to overlie the ends of the stand or bearing.

3. A fibrous bearing block for whip roll stands or the like, said block being relatively long and provided on its upper surface, intermediate its ends, with a transversely extending recess and on its under surface 55 with relatively deep transversely extending recesses forming longitudinally spaced projections.

In testimony whereof I hereunto affix my signature in the presence of two witnesses.

JESSIE B. WILLIAMS.
